UNITED STATES PATENT OFFICE

159,143

BRASSIÈRE

Fernand Desrochers, Quebec, Quebec, Canada, assignor to Dominion Corset Company Limited, Quebec, Quebec, Canada

Application December 19, 1949, Serial No. 6,728
In Canada November 9, 1949

Term of patent 14 years

(Cl. D20—4)

To all whom it may concern:

Be it known that I, Fernand Desrochers, a Canadian citizen, and resident of the city of Quebec, in the Province of Quebec, Dominion of Canada, have invented a new, original, and ornamental Design for a Brassière, of which the following is a specification, reference being had to the accompanying drawing, forming a part thereof.

In the accompanying drawings:

I claim:

The ornamental design for a brassière, as shown.

FERNAND DESROCHERS.
